Pulley Conversion of Cornfield Maine
Letters Patent

The Article referred to in these Letters Patent and on which my first of the
same containing a description of the machinery of the said "Pulley Conversion
consists of the improvement in the driving machinery, for threshing and
cleaning grain of all kinds.

"I call to whom these presents shall come. Be it known that I
the said Joshua Garrison of Cornfield in the County of Oxford and
State of Maine, year and year, have invented a new and useful improvement
consisting in the art or process of threshing and cleaning grain, sometimes
for threshing and cleaning all kinds of grain, & of which the following
is. Specification is, a full and exact description of the construction &
operation as invented and improved by me.

1. I make a frame thirty inches high and five feet long, the sides
of plank and thirteen inches wide on the clear, on the upper side of
the frame, and at the back end, I hang my beater or threshing wheel
thirteen inches long and eighteen inches in diameter. I then nail flat
nails on the rest of the length of the frame 14 planks ~~in~~ ⁱⁿ ~~wide~~ ^{wide}
and of the threshing wheel rising one inch on the whole length
from the threshing wheel to the front end of the frame, on this inclined
plain the grain is fed into the machine as it is threshed.

2. The threshing wheel is made and put together in the following
manner. The shaft of the wheel is round iron about one and a half
inches broad turned true. Within the bearing on this shaft, I put two
red iron heads, five eighths . . . . inch thick and nineteen inches in
diameter, and thirteen inches apart from each other to outside. These heads
would go on head on to the shaft and are made fast so as not to turn
round on it by a fit of iron let into the shaft and into the head on
the inside. Some iron bands roll this fit from a ditch, a
quarter inch on the inside of each head with one quarter inch
of the circumference all round, and one quarter inch deep, and half
an inch wide, to receive and hold the ends of the slats which make

the board of the wheel. These stones are made of cast iron about two and a half inches long half inch thick and four and a half inches wide, so that twelve stones just make the circumference of the wheel. I have three teeth on the outside of each stone. These teeth are so placed on the stone that by alternately shifting the ends of the stones from left to right the teeth on one stone come exactly between the teeth on the other stone all round the wheel. The ends of these stones are set into the grooves in the two heads, aforesaid. These teeth are cast with the stone stick, and are about two inches long one and a half inch broad, and three quarters of an inch thick at the but, and half that size at the top, and a true taper from the but to the point. I have six teeth also standing out on the circumference of each head, about one and three quarters inches long to come level with the tops of the teeth on the stones. These teeth also do their part in threshing; these stones are held into the grooves in the heads by six bolts which pass through under every other stone, from one head to the other, having having a head on one end and a nail on the other by which the heads and stones are brought firmly together. I have put but six stones on the threshing wheel in my model. Through I build the operative machine with twelve as above described. 3. The threshing wheel above described plays in the centre segment of about one quarter of a circle about twenty inches in diameter placed in front of the fuel and racking from the horizontal centre in front to the perpendicular centre, or a little beyond on the under side. This segment is made of six stones set in a circle of about twenty inches... diameter. These stones are of cast iron half inch thick and about three inches wide and fourteen inches long. Each end of this is set in a circular groove set in the inside of the frame about half an inch deep. I have four teeth on one stone and four on the other of the same dimensions as the teeth on the stones on the wheel. These stones, having four teeth are placed alternately with those having four teeth, one after the other, and the teeth are so placed on the respective stones that the teeth on one stone come exactly between the teeth on the other stone, and these teeth

on the stones in the course of the teeth on the cylinder which is on the two sides and the other. By this means the grain is shifted from one set of teeth to the other which makes it more certain to thresh clean. It has a stone on each side of the frame in each end of each stone in the course segment, by which each stone in this case can be set and moved readily, so as to bring the teeth on each in the concave exactly between the teeth on the wheel. Then I fix three or four long bolts across the machine under the segment to hold the stones firm in their places. The distance between the ends of the teeth on the wheel and segment should be about one eighth of an inch, and also between the teeth on the wheel and the teeth on the segment as they pass each other, or so large a segment as to admit the kernels of grain. . . . To pass through these segments without being broken or twisted. It. I put a pulley about six inches . . . . in diameter, and four broad, on one end of the shaft around which a belt passes from the large pulley on the horse power by which this thresher is put and kept in motion.

5. The above described thresher is connected with another machine, called a horse power by a belt, which is built and put in such as follows. I build a frame eleven feet long, six feet eight inches high, and eighteen inches wide in the clear, and planked on the inside and at the front end. At the fore end I place a black wheel two feet in diameter, and at the after end another black wheel eighteen inches in diameter. The circumference of the fore end wheel is divided into twelve equal parts, and these sections are made flat and give all new pitch wheel and a cog of proper size is built on each near each end. The after black wheel is left round. These wheels have a cast iron shaft of proper length with a flange on each bearing about six inches diameter and plank are bolted on to these to make the hubs. Between these black wheels put eight stationary setting pins, each in diameter, their upper sides being level with the black wheels. Then I put two stationary setting pins between these black wheels on the outer side, their upper surfaces being two inches below

letter chain, and as he pulls the chain in one time the chain moves the forward block wheel. The odds... in diameter between the two block wheels having the under sides level, makes the upper section of the chain an inclined plane of six inches in the whole length which gives the Horse a great advantage. The Horse is harnessed to the hind part of the machine by a pair of traces or has a hiffletree as to a carriage. 8. On the outside of this Horse there is a machine, is a cog wheel hoop in diameter which meshes into a bundle head of six inches diameter. This large cog wheel is fastened on to one end of the shaft of the forward block wheel. On the other end of the shaft of this bundle head, is a pulley three feet in diameter. This Horse power machine and the thresher machine are placed beside each other, so that a belt is passed round this large pulley on the end of the shaft of the bundle head, and round the pulley on the end of the shaft of the thresher. In this way the threshing machine is put and kept in motion. These two machines standing on one platform, may be so fixed that one may be moved under it by several wedges by which way the band may be tightened or slackened. Any of the above dimensions may be raised as convenience may require.

In the above specification I have described and set forth all the several parts of the aforesaid machines but I do not claim them as my invention. The parts that I claim as my own invention are the peculiarity of constructing and putting together the threshing machine. That is those parts of it that are made of cast iron and also the peculiarity of constructing & putting together the several segments. On the Horse power I claim only the peculiarity in sum of constructing the belt band or chain on which the Horse has and the manner of putting it together. In testimony that the above is a true specification of my said improvement as above described I have at this my hand this ninth day of January in the year of our Lord one thousand eight hundred and thirty five.
